MICROMETRIC ATTACHMENT FOR COMBINATION SQUARES

Frank Rothe, Garfield, N. J.

Application June 11, 1940, Serial No. 339,879

2 Claims. (Cl. 33—165)

This invention relates to mechanics' tools, more particularly to combination squares, consisting of a graduated blade having one or more adjustable heads slidable therealong and provided with means to retain them fixed when in adjusted position.

Such tools are commonly in use in machine shops and factories, serving their purpose satisfactorily, but are not adapted for accuracy and making close measurements such as are often required.

It is therefore the purpose of the present invention to provide simple attachments whereby measurements may be made with precision, limited in length only by the length of the blade 15 on which they are mounted.

A further feature is in the provision of micrometric attachments for combination squares, settable by gages of known accurate length, whereby a correct reading is obtained, wholly irrespective 20 of graduations on the blade of the square.

Another purpose is to produce simple, inexpensive means whereby a combination square may be readily transformed into a measuring instrument for obtaining exact results.

These advantageous aims are accomplished by the novel and entirely practical construction, combination and arrangement of parts herein-after described and illustrated in the accompanying drawing, constituting a component of this disclosure, and in which:

Figure 1 is a side elevational view of an embodiment of the invention, showing its application.

Figure 2 is a top plan view of the anvil block.

Figure 3 is a sectional view taken on line 3—3 of Figure 2.

Figure 4 is a side elevational view of the micrometer head mounting.

Figure 5 is a partial edge, partial sectional view 40 of the same.

Figure 6 is an end view thereof.

Referring in greater detail to the several views, Figure 1 shows a common form of combination square, the same consisting of a blade or rule 15, which is usually provided with graduations 16, either English or metric, and having in one side, intermediate its width, a channel 17 extending throughout its entire length.

Slidably mounted on one edge of the blade 50 is a head 20, slotted to closely straddle the sides of the blade, to which it may be adjustably secured by the clamp nut 21.

One of the faces of the head is finished to extend outwardly at a right angle from the blade 55

and is provided with opposed outstanding edges 22 arranged in parallel; this head may be furnished with a level and scratch point, all parts being of the usual, well known construction.

A bracket 25 is shaped to engage the face and edges 22 of the head and provided with clamp screws 26 to bind against the rear surfaces of its edges, retaining the bracket rigidly thereon; extending oppositely outward is a socket 27 adapted to contain a hardened steel ball 28, drawn by the screws against the face 22 to project centrally outward.

A slide 30 is movable along the blade 15 to which it may be firmly secured, in any adjusted position, by a clamp nut 31, engaged on a bolt 32, having an offset head movable in the channel 17; a right angled arm 33, formed with the slide, is similarly provided with a clamp nut 34 engaging a bolt 35 having an offset head 36.

A bar 40 of rectangular cross section, but having an angular rear edge 44 to fit the arm, is formed with a notch 41 to engage the head 36; in the upper enlarged portion 42 of the bar is a cylindrical opening 43 adapted to receive the front end of a micrometer stem 45.

This stem extends from an enlarged circular boss 46, adjacent a graduated barrel 47, around which the graduated sleeve 48 is rotatable in moving the spindle 49 through the barrel; the micrometer elements, like the blade and head, not being part of the invention.

The stem 45 is clamped in the bore 43 by a wedge plug 50, drawn into contact by a screw 52 threaded into the bar enlargement 42.

In operation, the micrometer being fixed in the bar 40 and the bar clamped to the arm 33, the ball 28 is adjusted to align with the spindle 49; thereafter a gage rod (not shown) of definite length is entered between the ball 28 and spindle 49, the micrometer set at some known point and the slide 30 adjusted along the blade.

Obviously measurements may be taken of work parts entered between the ball and spindle, and the lengths of such work parts determined by plus or minus readings of the micrometer from its setting.

The limit of length of work part is dependent only on the length of the blade, and the accuracy of the implement is limited only by the perfection of the micrometer, while the cost of the appliance is inconsiderable as compared with a measuring tool of equal efficiency.

I claim:

1. In a measuring tool having a blade and a pair of heads each adjustable therealong, one of

said heads presenting a face at a right angle to the blade and provided with opposed outwardly extending lateral edges, a bracket engageable on said edges, means to secure said bracket in adjustment thereon, a socket formed on said bracket, a ball carried in the socket having a portion of its periphery extending therebeyond, and a micrometer mounted in the other of said heads in register with said ball.

2. In a measuring tool having a blade and a pair of heads each adjustable therealong, one of

said heads presenting a face at a right angle to the blade and provided with opposed outwardly extending lateral edges, a bracket adjustable along said face and edges towards and from said blade, a ball held in said bracket to extend outwardly therebeyond, a bar adjustably clamped to the other of said heads, and a micrometer removably attached to said bar, said micrometer having its spindle directed towards and in register with said ball.

FRANK ROTHE.
